UNITED STATES PATENT OFFICE.

LESTER P. BARLOW, OF DETROIT, MICHIGAN.

ENGINE-COOLING SYSTEM.

Application filed December 30, 1926. Serial No. 157,901.

This invention relates to improvements in vapor or steam cooling systems for internal combustion engines, such as are used for automotive and other purposes.

5 In my copending application Serial No. 127,257, filed August 5, 1926, I have shown, described, and claimed a system in which a chamber is employed through means of which the level of liquids in the cylinder jackets of the engine is automatically regulated. This chamber is connected with the steam or vapor space of the jackets and with the liquid supply reservoir for the system in such a manner that steam generated in 10 said space may enter the reservoir from said chamber and have a heating effect on the cooling liquids in the reservoir. While this is not a serious objection, especially when the reservoir is of a size sufficient to hold 15 a relatively large body of water so as to counteract the heating effect of the steam or the water therein, yet it is desirable to prevent steam from entering the reservoir, and such is one of the objects of the invention 20 as set forth in this present application. To accomplish this object, I provide a permanent liquid seal in the connection between the liquid level regulating chamber and the reservoir so as to prevent steam from reaching 25 the reservoir from said chamber.

Another object of my present invention is to prevent the cooling liquids which have already entered the engine jackets from flowing backwards through the system to 30 the supply tank or reservoir. By retaining these liquids in the jackets after the motor has stopped, the motor can be kept warmer for a longer period than would be possible if the jackets were allowed to drain or 35 empty into said reservoir when the pump of the motor stops, as when the engine ceases to operate.

Another object of my invention is to suspend my forcing unit or pump of the system in the supply reservoir in such a manner as to prevent leakage of water out of the reservoir through the bearing where the shaft or propelling element of the pump enters the reservoir.

50 A still further object of my invention is to divide the liquids of the supply, one portion being adjacent to the pump or forcing means, and the other portion of the supply separated from the former by a substantially 55 tight bulkhead or partition wall with but

two openings through the same, one an exceedingly small hole at the top of the partition or bulkhead to permit air to pass between the two sections and a small hole through the lower portion of the partition to permit a limited flow of water between the sections, thereby reducing to the minimum the escape of liquids by evaporation through the vents in the reservoir.

60 Another object of my invention is to eliminate the loss of vapors through the vent of the condenser, and I vent my condenser at the cold side directly into the supply tank or reservoir, thereby removing the ejection effect heretofore caused by the condenser fan creating a draft adjacent to the vent opening. The great volume of air 65 passing the vent at the cold side of the condenser has caused considerable loss of moisture due to absorption and ejection due to the velocity of the air passing adjacent to the vent opening. These two objections I 70 have eliminated as stated above.

75 The invention consists further in the matters hereinafter described and claimed.

80 In the accompanying drawing—

85 The single figure is a diagrammatic view illustrating an internal combustion engine equipped with a vapor cooling system embodying the features of my invention.

90 In the drawing, 1 indicates a water or cylinder jacket of an internal combustion engine; and 2, a steam dome or space above the liquid level in the jacket. A condenser 3, which may be of the usual automobile radiator type to fit in with present automobile design, is located in front of the engine with an air circulating fan 4 between them, as shown. A conduit 5 connects the steam space 2 and condenser 3 at their upper ends, 95 so as to convey steam to the condenser during the operation of the system, the steam being condensed as it passes down through the condenser to be returned as condensate from the bottom of the condenser to the 100 system.

105 The cooling liquid circuit is arranged to supply liquids to the cylinder jacket 1, without circulating any of the cooling liquids through said jacket. This conduit includes a tank 6 located above a supply tank or reservoir 7. The tank 6 is divided by a partition wall 8 into two chambers 9, 10. Located in the reservoir 7 is a positive force pump 11, connected with one of the mov- 110

ing parts of the engine so as to be driven thereby; although the pump could be independently driven, if desired. A conduit 12 leads upward from the discharge of the pump 11 into the chamber 9, so as to supply liquids thereto from the reservoir 7 during the operation of the pump. A conduit 13 connects the lower portion of the chamber 9 with the jacket 1, preferably at its lower end so that liquids may be supplied to the jacket from said chamber by gravity. The liquid level to be maintained in the jacket 1 is indicated by a , and it will be noted that the tank 6 is so disposed with respect to this level that the chamber 9 has portions extending above and below the same. The conduit 12 extends up through the bottom wall of the chamber 9 to approximately the level a to be maintained in the jacket, so that no opportunity is afforded for any of the liquids in the jacket to drain back into the reservoir 7 when the engine is idle, as is the case in the arrangement shown in my copending application as aforesaid.

25 The chamber 9 has a return connection with the reservoir 7, so as to allow the excess liquids pumped into the chamber to return to the reservoir 7 without passing through the jacket 1. This return connection includes a substantially U-shaped conduit extending downward from the tank 6 and having one upright leg 14 opening into the chamber 9 and the other leg 15 opening into the chamber 10, the upper ends of these legs extending into their respective chambers so that the overflow liquids may pass from chamber 9 into chamber 10 through the legs of the conduit, as indicated in the drawing. To maintain a substantially constant liquid level in the jacket 1, as at a for instance, the leg 14 of this U-conduit extends up into the chamber 9 to approximately this level so that all liquids in excess of that required for such level will overflow through the conduit into chamber 10, and from thence be delivered back to the reservoir 7 through an outlet conduit 16.

Inasmuch as the levels in the steam space or dome 2 and the chamber 9 will correspond, it is desirable to have the pressures in these chambers substantially equal so that there may be a substantially automatic supply of liquids from chamber 9 to jacket 1 to compensate for the evaporation of the liquids in jacket 1, during the steaming action. Due to the possible resistance to the steam entering and passing through the condenser 3 caused by wall friction and capillary attraction, a back pressure will at times be produced on the surface of the water level in the jacket 1. To balance chambers 2 and 9, I provide a conduit 17 connecting chamber 9 with steam conduit 5 so that the pressures on the levels in chambers 2 and 9 will be maintained the same. With the outlet for

liquids being through the U-tube, the latter remains constantly filled with liquids and, therefore, provides a permanent liquid seal between the chamber 9 and the reservoir 7, so as to prevent the steam in chamber 9 from entering the reservoir 7 to impart heat thereto as is possible in the arrangement shown in my said copending application. Moreover, by preventing steam from entering the reservoir 7, no opportunity is afforded for the steam to escape through the vent of the reservoir and be wasted as in said application.

To prevent any possibility of the U-tube siphoning into the reservoir 7 and thus becoming ineffective as a liquid seal, I provide a pipe or conduit 18 connecting the upper end of the chamber 10 with the upper portion of the reservoir 7, so that chamber 10 may vent to the reservoir 7, the latter having a vent 19 to the atmosphere through a cap on the filling neck 20, as shown. Instead of having the outlet conduit 16 and the outlet leg 15 of the U-conduit separate and opening respectively into chamber 10, these pipe sections may be directly connected by a return bend and the vent tube 18 may be connected to the highest point of this bend.

A partition wall or bulkhead 21 divides the reservoir 7 vertically into two compartments having no communication with each other except through two relatively small upper and lower openings 22, 23 in said partition. The filling neck 20 opens into one of these compartments and the condensate from the condenser 3 is delivered to the other compartment through a suitable conduit 24. This last named compartment contains the pump 11 and has the return conduit 16 and the vent tube 18 opening into the same. At times the condensate entering the pump compartment will be at a higher temperature than the liquid contained therein, and will increase the temperature of the same. When alcohol is used to prevent freezing of the system, these heated liquids will have a tendency to vent off alcohol vapors. Their escape through vent 19, in this case, will be restricted to the minimum by the small aperture 22, and thus prevent excessive waste of the alcohol. The lower opening 23 is larger than the upper opening 22, but still small enough to restrict any rapid circulation of the liquids between the two compartments, therefore retarding the transferring of heat to the filling side of the reservoir.

The lower end of the condenser 3, above the drain 24, is connected by a conduit 25 to the supply tank 7 on its vent side, which is out of the influence of the fan 4 or the flow of air through the condenser. Thus the vent from the condenser is remote from this air, and no liquids or vapors are drawn out of the vent by such air to reduce the volume

of the liquids or vapors in the system as when the vent for the condenser is within the influence of these blasts.

As shown in the drawing, the lower or 5 loop end of the U-conduit extends into the reservoir 7 through its top wall. A relatively small drain hole 26 is provided in this loop end so as to permit the U-conduit to drain when the reservoir 7 is drained on re- 10 moving its drain plug 27, so that the entire circuit will be empty when drained. The cylinder jackets will not drain through the plug 27, so I provide a separate drain cock 28, tapped into the lower end of the jacket, 15 preferably at the connection with the supply conduit 13, as shown in the drawing. The normal level of the liquids in the reservoir is indicated approximately at b.

As shown in the drawing, a bracket 29 20 extends down into the pump compartment of the reservoir 7 to suspend the pump 11 therein. The driving shaft 30 for the pump extends upward through the top wall of the reservoir 7, and thus permits the pro- 25 vision of bearings without the use of packing, inasmuch as the bearing is always maintained above the maximum level of the water in the reservoir.

The details of structure and specific ar- 30 rangement of parts may be variously changed and modified without departing from the spirit and scope of my invention.

I claim as my invention:

1. In a vapor cooling system for internal 35 combustion engines, the combination with a cylinder jacket having a steam space above the same, of a liquid circuit connected with the jacket for feeding liquids thereto, said circuit including a chamber to regulate the liquid level in the jacket, a supply reservoir 40 for the chamber, and an outlet connection between said chamber and the reservoir and formed to provide a permanent liquid seal between them so as to prevent steam flowing 45 into the reservoir from said chamber.

2. In a vapor cooling system for internal 50 combustion engines, the combination with a cylinder jacket having a steam space above the same, of a circuit whereby a cool- 55 ing liquid may be continuously circulated without passing through said jacket, said circuit including a chamber to regulate the liquid level in the jacket, a supply reservoir for said chamber, and an outlet connection between said chamber and the reservoir and formed to provide a permanent liquid seal 60 between them so as to prevent steam flowing into the reservoir from said chamber.

3. In a vapor cooling system for internal 65 combustion engines, the combination with a cylinder jacket having a steam space above the same, of a liquid circuit connected with the jacket for feeding liquids thereto, said circuit including a liquid level regulating 70 chamber for the jacket and a supply reser-

voir for said chamber, and a substantially U-shaped conduit forming a permanent liquid seal in the connection between the chamber and the reservoir to prevent steam flowing into the reservoir from said chamber, said conduit having its discharge and return ends at approximately the normal level for the liquids in the jacket for maintaining such level and a corresponding level 75 in the chamber.

4. In a vapor cooling system for internal combustion engines, the combination with a cylinder jacket having a steam space above the same, of a circuit connected with the jacket for feeding liquids thereto, said circuit including a liquid level regulating chamber for the jacket and a supply reservoir for said chamber, and a substantially U-shaped conduit forming a permanent liquid seal in the connection between the chamber and the reservoir to prevent steam flowing into the reservoir from said chamber, said conduit having its discharge and return ends at approximately the normal level for the liquids in the jacket for maintaining 80 such level and a corresponding level in the chamber, and means venting the return end of the conduit to the upper portion of the reservoir to prevent siphoning of the con- 85 duct.

5. In a vapor cooling system for internal combustion engines, the combination with a cylinder jacket having a steam space above the same, of a liquid circuit connected with the jacket for feeding liquids thereto, said circuit including a liquid level regulating chamber for the jacket and a supply reservoir for the chamber, said reservoir being located below said chamber, and a substantially U-shaped conduit forming a permanent liquid seal in the connection between the chamber and the reservoir, said conduit having its loop end in the reservoir and provided with a relatively small leak aperture 100 so that the conduit may automatically drain 105 through the reservoir on draining the system.

6. In a vapor cooling system for internal combustion engines, the combination with a cylinder jacket having a steam space above the same, of means providing a circuit whereby a cooling liquid may be forcibly and continuously circulated without passing through said jacket, said circuit including a chamber connected with the jacket for feeding liquids thereto and for maintaining a substantially constant level therein, and a supply conduit having its discharge end in the chamber at approximately the same level as maintained in the jacket so as to prevent 115 draining of the jacket when the engine is idle.

7. In a vapor cooling system for internal combustion engines, the combination with a cylinder jacket having a steam space above 120

the same, of means providing a circuit whereby a cooling liquid may be forcibly and continuously circulated without passing through said jacket, said circuit including a 5 supply reservoir and a chamber, said chamber being above the reservoir with the chamber disposed to extend above and below the liquid level to be maintained in the jacket, means connecting the chamber with the 10 reservoir and jacket, respectively, for supplying liquids to the latter, and an overflow conduit connecting the chamber with said reservoir with the inlet end of said conduit at approximately the level to be maintained 15 in said jacket.

8. In a vapor cooling system for internal combustion engines, the combination with a cylinder jacket having a steam space above the same, of a condenser connected with said 20 steam space, means providing a circuit whereby cooling liquid may be forcibly and continuously circulated without passing through either the condenser or the jacket, a conduit leading from the circuit to the 25 jacket, said circuit including a supply reservoir divided into two compartments by a partition wall, said partition wall having restricted upper and lower openings for air and liquids, respectively, an air vent for the 30 system opening into one compartment, a force pump and condensate return from the condenser being in the other compartment.

9. In a vapor cooling system for internal combustion engines, the combination with a 35 cylinder jacket having a steam space above the same, of means connected with the jacket for supplying liquids thereto and also

providing a circuit whereby the cooling liquids may be forcibly and continuously circulated without passing through the jacket, 40 said circuit including a supply reservoir connected with the inlet and return ends of the circuit, a pump in said reservoir for forcing liquids through the circuit, and means for suspending the pump in the reservoir with 45 the bearing for the operating member of the pump above the level of the liquid in the reservoir so that no packing is necessary for said bearing.

10. In a vapor cooling system for internal 50 combustion engines, the combination with a cylinder having a steam space above the same and a condenser connected to said space, of means for supplying cooling liquids to said jacket, and an atmospheric vent 55 directly connected with the condenser and disposed out of the path of air flow through the condenser so that the passing air will have no ejection or absorption effect on said vent.

11. In a vapor cooling system for internal combustion engines, the combination with a cylinder jacket having a steam space above the same and a condenser connected with said space, of means for supplying cooling liquids to the jacket, including a supply 65 reservoir located below the condenser, an atmospheric vent means for the reservoir, and a conduit connecting the lower portion of the condenser above its condensate outlet with the venting means of the reservoir. 70

In testimony whereof I affix my signature this 27th day of December, 1926.

LESTER P. BARLOW.
